(57) **CLAIM**

The ornamental design for an attache case, as shown and described.

DESCRIPTION

FIG. 1 is a perspective view of the attache case embodying my new design.

FIG. 2 is a front view of the attache case shown in FIG. 1, the rear view being a mirror image thereof.

FIG. 3 is a left end view thereof, the right end view being a mirror image thereof.

FIG. 4 is a top view thereof; and,

FIG. 5 is a bottom view thereof.
